UNITED STATES PATENT OFFICE.

ALBERT A. COYLE AND WILLIAM S. MITCHELL, OF ST. LOUIS, MISSOURI.

CHOCK.

Application filed April 23, 1925. Serial No. 25,452.

To all whom it may concern:

Be it known that we, ALBERT A. COYLE and WILLIAM S. MITCHELL, citizens of the United States, residing at city of St. Louis, 5 State of Missouri, have invented a new and useful Chock, of which the following is a specification.

This invention relates to improvements in chock construction, and aims to provide 10 a chock especially designed for heavy duty.

An important object of the invention is the provision of a chock so constructed that it will be exceptionally strong and durable, and one wherein the friction between the 15 movable element and its support, is reduced to the minimum; thereby materially increasing the efficiency of the chock.

A still further object of the invention is to provide a chock of this character constructed to withstand lateral strain usually 20 directed to the pin or spindle of a chock and to distribute the strain throughout the entire body of the chock base, to the end that the strength of the chock is greatly increased and the weight thereof decreased.

Another important object of the invention is to provide means to facilitate the lubrication of the working parts, the housing being constructed to exclude foreign elements 25 from the moving parts of the chock to reduce wear to the minimum.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 35 within the scope of what is claimed, without departing from the spirit of the invention.

Referring to the drawing:

Figure 1 is a vertical sectional view 40 through a chock constructed in accordance with the invention.

Figure 2 is a sectional view taken on line 2-2 of Figure 1.

Figure 3 is a sectional view taken on line 3-3 of Figure 1.

50 Referring to the drawings in detail, the

reference character 5 indicates the body portion of the chock, which is provided with a flange 6 at its base, which flange is formed with suitable openings to accommodate the securing members 7 that also extend through the supporting surface 8, on which the chock is mounted.

The flange 6 is cut away defining a shoulder 9 and a roller supporting surface 10 on which the rollers 11 are positioned, the 60 rollers being designed to engage the drum 12 which is mounted on the base 5.

The upper end of the body portion 5 is cut away defining a shoulder 13 on which the rollers 14 rest, the rollers being 65 designed to engage the depending flange 15 formed on the upper end of the drum 12 so that lateral strain directed to the chock will be directed to the rollers 14 to the end that the drum may move freely over the body 70 portion 5.

Forming a part of the base 5 is a reduced end portion 16 which is threaded at 17 to receive the nut 18 which nut is adapted to contact with the drum to hold the drum in 75 position on the base 5. Formed in the upper end of the drum 12 is an opening 19 through which a lubricant may be directed to the rollers 14 and 11.

As clearly shown by Figure 1 of the 80 drawing, the chock is formed with a peripheral groove for the reception of a cable or rope to prevent the cable or rope used in connection with the chock from slipping upwardly from the chock when strain is 85 brought to bear thereon.

We claim:

In a device of the character described, a body portion having a flange formed at its base, said flange having a cut away portion 90 defining a shoulder, and a substantially flat supporting surface directly above the shoulder, a drum mounted on the body portion and having a depending lower portion adapted to operate adjacent to the shoulder, roller bearings mounted on the supporting surface and engaging the body portion and depending lower portion of the drum, a depending flange formed on the inner surface of the upper portion of the drum, 100

roller bearings mounted on the body portion adjacent to the upper end thereof, said flange adapted to engage the roller bearings at the upper end of the body portion, said body portion having a reduced upper end portion, and said drum having an opening to accommodate the reduced upper end por-

tion of the body portion to secure the drum to the body portion.

In testimony that we claim the foregoing as our own, we have hereto affixed our signatures.

ALBERT A. COYLE.
WM. S. MITCHELL.
